UNITED STATES PATENT OFFICE

146,283

DESIGN FOR A CLOCK CASING

George H. Kress, Vestal, N. Y., assignor to International Business Machines Corporation, New York, N. Y., a corporation of New York

Application November 13, 1946, Serial No. 134,749

Term of patent 14 years

(Cl. D42—7)

To all whom it may concern:

Be it known that I, George H. Kress, a citizen of the United States and residing in Vestal, county of Broome, and State of New York, have invented a new, original, and ornamental Design for a Clock Casing, of which the following is a specification, reference being had to the accompanying drawing, forming part thereof.

Fig. 1 is a perspective view of a clock casing showing my new design.

Fig. 2 is a side elevational view thereof.

Fig. 3 is a top plan view thereof.

I claim:

The ornamental design for a clock casing, substantially as shown.

GEORGE H. KRESS.
